(57) **CLAIM**

The ornamental design for a medical head immobilizer as
shown and described.

DESCRIPTION

1. Medical head immobilizer

1.1 : Perspective

1.2 : Front

1.3 : Back

1.4 : Left

1.5 : Right

1.6 : Top

1.7 : Bottom

(Continued)

In the reproductions, the equal-length broken lines depict portions of the medical head immobilizer that form no part of the claimed design.

This design is characterized in the combination of shape and form of "medical head immobilizer" which is a device used for CPR and by which angle and height of patient head is adjustable when immobilizing the patient head.
